AUTOMATIC LUBRICATOR FOR TAILSTOCK CENTERS

John Turenhalk and Harry Turenhalk,
Yonkers, N. Y.

Application July 21, 1944, Serial No. 545,956

5 Claims. (Cl. 184—46)

1

The invention relates to a lubricator, and more especially to an automatic lubricator for a tail stock center.

The primary object of the invention is the provision of a lubricating device of this character, wherein the lathe centers, especially a tail stock center, will be automatically lubricated constantly, thereby saving valuable time in this direction, in that hand oiling is eliminated, and a decrease of the work going off center due to excessive wearing of the tail stock, which might result in untrueness of the work.

Due to careful attention necessary for accurate work on the lathe, lathe centers, especially the tail stock center, must be either well oiled or greased from time to time for satisfactory operation, but in due time, especially if the center is unhardened there is a bruising of the same, after some work is turned out, this being remedied by grinding the tail stock center from time to time.

Another object of the invention is the provision of an automatic lubricating device, wherein the above difficulties will have been overcome, and in this manner the device is a time saver.

A further object of the invention is the provision of a device of this character, which is simple in construction, thoroughly reliable and efficient in operation, strong, durable, a positive lubricant feed control, and inexpensive to manufacture and install.

With these and other objects in view the invention consists in the features of construction, combination and arrangement of parts as will be hereinafter more fully described, illustrated in the accompanying drawing, which shows the preferred embodiments of the invention, and pointed out in the claims hereunto appended.

In the accompanying drawing:

Figure 1 is a top plan view of a tail stock for a lathe showing the lubricating device constructed in accordance with the invention installed, the peen of the center being broken away in part.

Figure 2 is a fragmentary side elevation.

Figure 3 is a sectional view taken on the line 3—3 of Figure 2 looking in the direction of the arrows.

Figure 4 is a fragmentary vertical sectional view of a slight modification.

Figure 5 is a plan view of one of the elements of the bellows assembly of the modified form of expandable and collapsible container.

Similar reference characters indicate corresponding parts throughout the several views in the drawing.

Referring to the drawing in detail, particularly

2

Figures 1 to 3, inclusive, A designates generally the body of a tail stock for a lathe, and is of standard construction, having the advancing and receding center 10 as usual, with its peen 11, in association with the lubricating device constituting the present invention and hereinafter set forth. The center 10, however, is modified for the attachment of the lubricator thereto, by having a longitudinal bore 22 extending inwardly from the end of the peen 11 and commonly connecting several lateral bores 21 opening radially outward the body of the center.

The device comprises a bellows-like expandable and collapsible container 12, having at its bottom a central discharge nipple 13, externally threaded at 14. This nipple 13 is passed through a companion hole in a shelf 15 of a hanger bracket 16, which is made secured to the stock body A at one side thereof, as at 17, the nipple being also connected by a detachable union 18 with a flexible duct 19, which extends to the center 10, where it is coupled therewith through a nipple 20 at any one of the radial bores 21.

The flexible duct 19 is fitted with a cutoff valve 23 adjacent to its connection with the center 10, so as to permit regulation of the flow of lubricant from the container 12 into the passage 22 for proper lubrication of the peen 11.

As before stated, the center 10 is provided with several lateral bores 21, radiating from the inner end of the longitudinal bore 22 that extends outward through the peen 11, and all of these, with the exception of the one in connection with the nipple 20, are closed off by Allen set screws 20', so that, when the center 10 shows a slight unevenness in wear, it may be compensated for by interchanging the nipple 20 with any one of the set screws 20', thus changing the relative position of the center with respect to the nipple and, consequently, that of the peen 11 with respect to the work.

The shelf 15 of the bracket 16 is formed with an upstanding rack 24 for sustaining the container 12 vertically, which is confined or held within the said rack 24 for the working thereof. The top of the container 12 is formed with an indented filling nipple 25 in which is removably threaded a closure plug 26, which on removal permits the filling of the container 12 with grease or oil for lubricating purposes.

Adapted to be superimposed on the top of the container 12 is one or more disk-like weights 27, these being confined within the rack 24 and function to exert pressure on the container 12 to

force lubricant therefrom for lubricating the center 10.

If additional pressure is required for forcing lubricant from within the container 12 there is created a weight hook or hanger 28, for the carriage of supplemental weights 29, which are similar to the weights 27. This hook or hanger 28 has a saddle 30 for resting upon a weight or weights 27 when superimposed on the top of the container 12, the mounting of the said hook or hanger 28 being clearly shown in Figures 2 and 3 of the drawing.

The center 10 is held in position by a key 31 which engages in the sleeve 32 of the center 10, as is shown in Figure 1 of the drawing.

In Figure 4 of the drawing there is shown a slight modification of the lubricant container, and, here, the top 33 thereof is in the form of an inverted, cylindrical cap, of metal, which has its end wall provided with the indented filling nipple 25', normally closed by a screw plug, and the edge of its side wall outwardly flanged, as at 33', which, in turn, has its edge upwardly beaded, as at 33''. The bottom 34 takes the form of a flat circular wall, having its edge beaded, as at 34', and provided with a downwardly extending nipple 33', opening through its center. The wall of the bellows, forming the body 12' of the container, is made up of a series of washer-like discs 35, stamped out from a suitable flexible material of a lubricant resistant character. These discs 35 have their inner and outer edges beaded, as at 35', with the beads of the inner edges on the sides of the discs opposite to those on which the beads at the outer edges are formed, so that, when the end portions 33, 34, and the discs 35 are brought into assembly, as shown, the juxtaposed

beads provide grips for the clinching over the same of metal rims 36. By this novel construction, the advantage of simplification and least expense, in the making and assembling of the container parts, is readily apparent.

What is claimed is:

1. In a lubricator of the class described, a collapsible container having the form of a vertically disposed bellows, with flat top and bottom end walls, the top wall having a centrally disposed inwardly nipped inlet for a supply of the lubricant, the bottom wall having a centrally disposed, downwardly extending, nipped outlet, a closure plug for the inlet, a flexible duct leading from the outlet, and a cutoff valve for controlling the lubricant discharge from the flexible duct.

2. The lubricator as in claim 1, with the top and bottom walls of metal and the bellows made up of a plurality of washer-like discs stamped out from a sheet of lubricant resistant material, the edges of the walls and discs being beaded and juxtaposed, when in assembly, to provide grips for the clinching of metal retaining rims thereover.

25 3. The lubricator as in claim 1 wherein there is provided changeable weight means for exerting pressure on said container for forcing lubricant therefrom through said duct.

4. The lubricator as in claim 1, wherein there is provided a rack for sustaining the container in working position.

30 5. The lubricator as in claim 1, wherein there is provided a removable weight hanger for association with the container.

JOHN TURENCHALK.
